(57) **CLAIM**

The design for a set of measuring instruments comprising clock, a weather station (barometer), a rain gauge, a thermometer and temperature remote sensor, as shown and described.

DESCRIPTION

FIG. 1A is a front elevational view of a clock component according to the present design;

FIG. 1B is a left side and front perspective view thereof;
FIG. 1C is a right side and rear perspective view thereof;
FIG. 2A is a front elevational view of a weather station (barometer) component according to the present design;
FIG. 2B is a left side and front perspective view thereof;
FIG. 2C is a right side and rear perspective view thereof;
FIG. 3A is a front elevational view of a rain gauge component according to the present design;
FIG. 3B is a left side and front perspective view thereof;
FIG. 3C is a right side and rear perspective view thereof;
FIG. 4A is a front elevational view of a thermometer (combined with a hygrometer) component according to the present design;
FIG. 4B is a left side and front perspective view thereof;
FIG. 4C is a right side and rear perspective view thereof;
FIG. 5A is a back elevational view of a remote sensor component for the thermometer component;
FIG. 5B is a front elevational view thereof;
FIG. 5C is a right side elevation view thereof, the opposite side being a mirror image thereof; and,
FIG. 5D is a bottom view thereof.

The bottoms and tops of the components are not claimed. Also the indicia shown are not claimed. The components of FIGS. 1A-4A have substantially identically shaped housings with varying fronts having round displays and 3-4 press buttons. The remote sensor of FIGS. 5A-5D has a similar but more narrow housing. The components of the set of the present design are intended to be used together.
